UNITED STATES PATENT OFFICE

2,599,731

SHUTTLE CLEANER

Robert Whewell, Jr., Cleveland, Ohio, assignor
to The Warner & Swasey Company, Cleveland,
Ohio, a corporation of Ohio

Application August 25, 1949, Serial No. 112,233

7 Claims. (Cl. 139—125)

1

My invention relates to weaving machinery, especially machinery of the gripper shuttle type. It is an object of the invention to improve the handling and operation of gripper type shuttles. A further object is to maintain such shuttles and the jaws thereof, clean and free from lint, broken ends, oil, grease and other foreign material. It is likewise an object to avoid soiling cloth being woven and to avoid weaving imperfections and foreign substances into the cloth.

Still another object of the invention is to provide an improved way of lifting gripper shuttles to picking position from a conveyor belt while controlling the action of the thread receiving jaws and cleaning them. An object is to coordinate cleaning, lifting and thread gripping and clearing operations; and to enable the functions of the gripper shuttle to be performed with great rapidity, as well as to reduce to a minimum the period of time for transferring a gripper shuttle to the picker box from the conveyor belt which returns it from a receiving box to the picker side of the loom.

Other and further objects, features and advantages of the invention will become apparent as the description proceeds.

Although my invention is not limited thereto, my arrangement for simultaneous shuttle lifting and cleaning may be applied to a gripper shuttle loom of the general type disclosed in the co-pending application Serial Number 111,416, filed August 30, 1949, of Nicholas P. Darash, assigned to the same assignee as the present application.

In carrying out the invention in accordance with a preferred form thereof, I provide mechanism for lifting the shuttles from a shuttle returning conveyor to the picking position by sweeping each shuttle angularly, sidewise and upward through an arc of about ninety degrees. I am thus able to utilize greatly simplified, more reliable and durable mechanism, not only for the shuttle lifter, itself, but also for the auxiliary mechanisms performing other functions such as opening and closing thread grippers and locating the shuttle for the pick. Furthermore, I clean the shuttle while it is being lifted, without any additional movements and without causing any delay in the operations of the weaving machine.

A thread gripper operating mechanism is arranged to rotate with the shuttle carrier so as to open the thread receiving jaws and to hold them open while they are being swept by a cleaning brush.

The arrangement is such that the shuttles being returned from the receiving box may be con-

2

veyed on their side in a narrow compact shuttle return duct under the shed instead of being carried in a flat horizontal position resting on a conveyor belt as heretofore proposed, such as in Moessinger Patent No. 2,420,380, for example.

A better understanding of the invention will be afforded by the following detailed description considered in conjunction with the accompanying drawings, in which

10 Fig. 1 is a front view of a gripper-shuttle weaving machine representing one form of apparatus in which my invention may be employed, a front view being one from the cloth-beam side where the operator stands;

15 Fig. 2 is a right-end view, principally in cross-section of the apparatus of Fig. 1 represented as partially cut by a plane 2—2, indicated in Fig. 1;

Fig. 3 is an enlarged fragmentary view partly in section of the portion of the apparatus of Figs.

20 1 and 2, including the delivery end of the shuttle conveyor, the shuttle lifter, shuttle jaw opening mechanism, and the picking box represented as cut by a plane 3—3 indicated in Fig. 1;

Fig. 4 is a top plan view of a known type of 25 gripper shuttle, which may be employed in carrying out my invention, the shuttle being shown with closed weft-thread-receiving jaws;

Fig. 5 is a view corresponding to Fig. 4, with 30 weft-thread receiving-jaws held open, and showing in cross-section a portion of the frame-work supporting a shuttle cleaner brush;

Fig. 6 is an elevation partially in section of the 35 shuttle lifting mechanism of Fig. 3 with the shuttle in the lowermost position;

Fig. 7 is in view of the mechanism with the 40 shuttle in the picking position;

Figs. 8 and 9 are views corresponding to Figs. 45 6 and 7 respectively, of mechanism of Fig. 3 for opening the thread receiving jaws of the shuttle,

Fig. 10 is an enlarged fragmentary cross-sectional view of the portion of the apparatus of Figs. 1 and 2, including the delivery end of the shuttle conveyor, the shuttle lifter and the picking box represented as cut by a plane 10—10 indicated in Fig. 2.

Like reference characters are utilized throughout the drawings for designating like parts.

Referring to the drawings, in the form of 50 apparatus shown by way of illustration, the weaving machine comprises a supporting frame including a pair of side plates 21 and 22 (represented in Fig. 1) secured to cross members 23 and 24 shown in cross-section in Fig. 2. The weaving machine illustrated is of the gripper shuttle

type. In Fig. 1 there is visible a roll of cloth 25 which has been wound on a cloth beam 26. There are heddle frames 27 carrying heddles for the weaving machine. Shedding mechanism is enclosed within the housing 28 shown in Fig. 2 and one or more stationary spools or packages (not shown) are provided for the weft yarns or threads. The machine may be provided with shuttle picking and guiding mechanism of the general type illustrated in Patents 2,160,338, 2,160,339, 2,316,703 Moessinger and 2,099,667 Rossmann and thread-transfer apparatus of the type illustrated in Patent Number 2,163,760 Moessinger. Preferably, however, an improved form of shuttle conveying mechanism is employed.

In the apparatus represented in Fig. 1 there is an electric motor 31 for providing the driving power, which is adapted to drive both the main shaft 32 through a suitable drive such as a belt or a chain drive 33 and to drive an auxiliary shaft 34 through conventional gearing (not shown).

Referring to Fig. 2, the weaving machine includes a warp beam 38, heddle frames 27 carrying heddle eyes 39, a picker box 41 including lay mechanism 42, and the cloth beam 26.

During the operation of the weaving machine, warp yarns 52 are drawn from the warp beam 38 over a whip roll 51 and formed into a shed 53 by the operation of the heddles 27 controlled by the shedding mechanism 28. They are then drawn through the dents of a reed 54 carried by the lay mechanism 42 along conventional rolls 55 to the cloth beam 26 in the form of cloth 56. As in conventional gripper shuttle weaving machines, the weft threads thrown through the shed 53 by the mechanism in the picker box 41 are beaten in by the reed 54 to form the cloth 56.

As explained, all the gripper shuttles are thrown or projected from the picker box on one side of the shed through the shed to a receiving box (which may be conventional and therefore is not shown herein). It is, therefore, necessary to provide means for returning the shuttles to the picker side of the shed. For this purpose a shuttle-returning conveyor is provided. Preferably the conveyor takes the form of a passageway or duct 61, below the shed, having a cross-section corresponding to the cross-sectional shape of a shuttle 62 when turned over on its edge. A sprocket driven chain 63 is provided having lugs 64 all as shown in Fig. 10 for returning the shuttles 62 in succession from the receiving box, not shown, to the picker side of the machine, at which the mechanism shown in Figs. 3 and 10 is mounted. The picker box itself so far as it relates to the picking mechanism and the yarn delivery mechanism is also conventional and is, therefore, not specifically illustrated. However, the center line of the shuttle receiving cavity 57 of the picker box is at the level of the center line of the shaft 72 represented in Figs. 3 and 10 which constitutes the uppermost position of the shuttle 62 to which it must be lifted from its lowermost position, represented in Fig. 10 by the position of the shuttle 62.

A pivoted shuttle lifter, as illustrated in more detail in Figs. 6 and 7, is provided for lifting the shuttles 62 substantially through a 90° arc, thereby not only lifting them but turning them from the edge-down position, in which they are most conveniently returned by conveyor, to the flat or horizontal position in which they are projected by the picking mechanism.

My invention is illustrated as being employed

in conjunction with the conventional type of gripper shuttle of the form illustrated in Figs. 4 and 5 consisting of an elongated hollow metal piece or shell 65 having a nose 66 and containing a hair-pin type or U-shape spring 67 secured at the yoke by rivets 68 or the like, and having at the trailing end of the shuttle, scarcely projecting therefrom, a pair of thread receiving jaws 69. The spring 67 is so designed that it normally holds the jaws 69 together for securely gripping the end of a weft thread or yarn which has been presented to the shuttle by mechanism, not shown, from a stationary spool or package for enabling the weft thread to be drawn through the shed when the shuttle is projected through the shed or the picking mechanism.

Such shuttles are provided with an opening 71 of such dimensions that when a thread opener pin or the like is inserted in the opening 71, it spreads the tines 70 of the spring 67, thereby opening the jaws 69 to the position illustrated in Fig. 5.

When a shuttle 62 is in the picking position, the horizontal dimension of its cross-sectional outline substantially exceeds the vertical dimension. For lifting such a shuttle from the position at the end of the shuttle return conveyor illustrated in Fig. 3 to the picking position and turning it from the edge down to the horizontal position, a shuttle carrier 58 is provided as illustrated in Figs. 6 and 7 having an opening 59 adapted to receive the shuttle and the carrier 58 is secured to an arm 60 and pivoted upon a horizontal shaft 72. The shaft 72 is supported on a frame work 73 having an arcuate passageway 74 through which the shuttle carrier 58 and shuttle 62 are adapted to be swept during the shuttle-lifting operation.

Although the invention is not limited to the specific form of mechanism for rotating the shuttle carrier arm 58, preferably a cam and linkage mechanism is employed. For example, a barrel cam 75 may be provided secured to the auxiliary shaft 34 which rotates when the other auxiliary mechanism of the weaving machine is in operation. For cooperating with the barrel cam 75 there is a lever 77 pivoted at 78 having a downwardly extending arm 79 carrying a cam follower, for example, in the form of a rotatably mounted roller 81.

In order to avoid the necessity for springs or other mechanism for holding the cam follower 81 against the cam surfaces of the barrel cam 75, a cam groove 82 is preferably formed in the barrel cam 75 so as to control the axial motion of the cam follower 81 in either direction. The lever 77 has an upwardly extending arm 83 with a link 84 pivoted at one end to the upper end of the arm 83 and at the other end to the shuttle carrier arm 60. The cam groove 82 is so shaped that during a predetermined fraction of a revolution of the auxiliary shaft 34 corresponding to the period of time in which no picking action takes place, the lever 77 is rotated from the position shown in Fig. 6 to that shown in Fig. 7 so that the shuttle 62 is lifted from a lower position to the upper position. It will be understood that the shaft 34 is also synchronized with the mechanism driving the chain 63 with respect to the position of the lugs 64 so that each such lug 64 presents a gripper shuttle 62 to the carrier 58 and pushes it into the slot 59 when the shuttle carrier arm 60 is in a position illustrated in Fig. 6.

It is to be understood also that when the shuttle 62 is in the position illustrated in Fig. 7 it is in the proper position to be engaged by the

picking mechanism not shown which projects it through the shed 53.

In conjunction with the shuttle lifting mechanism, means are provided for opening the thread receiving jaws 69 of the shuttle as it is being lifted, in order to eliminate the necessity for an additional operation and the consequent reduction of maximum possible operating speed consequent upon opening the thread receiving jaws after the shuttle has reached the level of the picking position. To this end a second arm 85 is provided also pivoted upon the shaft 72. The arm 85 is provided with a more or less arcuately extending finger 86 adapted to enter the opening 71 of the shuttle 62 and having a thickness measured in the radial direction exceeding the space between the tines 70 of the thread receiving jaw spring 67 when the jaws 69 are closed.

Mechanism is provided for moving the arm 85 similar to that provided for moving the arm 60. Such mechanism, in the form of apparatus illustrated, comprises a lever 80 pivotedly mounted on a shaft 90 having a downwardly extending arm 87, and upwardly extending arm 88, a cam follower 89 at the end of the loweredly extending arm 87, and a link 91 joining the upward end of the arm 88 and the swinging jaw opener arm 85. A second cam groove 92 is formed in the barrel cam 75 for receiving the cam follower 89.

The cam grooves 92 and 82 are so cut, however, that initially, that is to say when the shuttle carrier 58 is in its lowermost position, the jaw opener finger 86 is in a retracted position as illustrated in Fig. 8, but as the shuttle carrier arm 60 begins to rotate counterclockwise so as to sweep the carrier 58 through an upward arc, the arm 85 advances with respect to the arm 60 and drives the jaw opener fingers 86 into the shuttle 62 during the early portion of the upward stroke of the carrier 58. Accordingly, the thread receiving jaws 69 are separated as the shuttle follows its arcuate upward path.

In order that the shuttle may also reach its upward position in which a length of thread drawn from the stationary spool or package is presented to it, without any grease, lint or broken threads or foreign material adhering to the thread receiving jaws 69, a cleaner brush 93 is mounted in the path of the shuttle and the open thread receiving jaws 69. Such a brush is illustrated in detail in Fig. 5. It is mounted at the position indicated schematically by the numeral 93 indicated in Figs. 6, 7, 8 and 9. For convenient mounting of the brush 93, consisting of a circular bundle of bristles, a brush mounting screw 94 is preferably provided. The screw 94 is adapted to be screwed into the frame work 73 and has an end socket 95 into which the bristles constituting the cleaner brush 93 are cemented.

The operation of the apparatus will be apparent from an examination of the drawings. Thus, as the auxiliary shaft 34, which is synchronized with the picker shaft 96 makes a quarter of a revolution, it moves the shuttle 62 from the lowermost position to the picking position. In the course of this motion, the thread receiving jaws 69 are opened by the action of the thread opener finger 86. The open jaws 69 are swept by the cleaner brush 93 and the foreign material is removed therefrom. Thereupon, further rotation of the shaft 34 and mechanism, not herein specifically described since it does not constitute part of the present invention, serves to present a new end of thread to the open jaws 69; and further rotation of the barrel cam 75 causes the

finger to be retracted causing the new length of thread to be gripped by the shuttle. During the next fraction of a revolution of the shaft 34, the picker mechanism is released projecting a shuttle through the shed 53.

Immediately upon the completion of this action, the shuttle carrier 68 now being empty, the form of the cam groove 82 is such as to retract also the carrier arm 60 to the position shown in Fig. 6. With this angular position of the shaft 34, the conveyor chain 63 and the lug 64 approach the position shown in Fig. 10. Further movement of the lug 64 moves the next shuttle 62 into the position shown in Figs. 10 and 6, in which the shuttle 62 is inserted in the opening 59 in the carrier 58. It will be understood that the shuttle conveyor duct 61 contains a plurality of shuttles 62 being returned and that there are a plurality of lugs 64 on the chain 63, so spaced that an additional shuttle 62 is presented to the carrier 58 each time it reaches the lowermost position represented in Fig. 6, namely once for each rotation of the auxiliary shaft 34.

While I have described my invention as embodied in concrete form and as operating in a specific manner in accordance with the provisions of the patent statutes, it should be understood that I do not limit my invention thereto, since various modifications thereof will suggest themselves to those skilled in the art without departing from the spirit of my invention, the scope of which is set forth in the annexed claims.

What is claimed is:

1. In a weaving machine of the gripper-shuttle type, the combination comprising a pivoted arm to which a shuttle carrier is secured for supporting a shuttle of the type having openable thread receiving jaws, a second pivoted arm formed with an opener for such thread receiving jaws, shuttle cleaning bristles mounted in the path of the thread receiving jaws of such a shuttle as such shuttle is swept through an arc by rotation of said pivoted shuttle carrier, and cam means with linkage means connecting said cam means to said shuttle carrier arm and said jaw opener arm for driving the jaw opener arm in advance of the shuttle carrier arm during the first part of its stroke whereby the thread receiving jaws are retained open during such part of the stroke as the shuttle is swept by the cleaner bristles.

2. In a weaving machine of the gripper-shuttle type employing a shuttle having openable thread receiving jaws, mechanism for moving such a shuttle to a pick position comprising an arm having a pivot at one end and a shuttle carrier at the other end, framework supporting such pivot whereby the arm may move a gripper shuttle through an arcuate path, and cleaner bristles mounted upon such framework in said path whereby the gripper shuttle is cleaned preparatory to being brought into the pick position.

3. In combination, a gripper-shuttle of the type having a pair of thread receiving jaws formed at the ends of a hair pin type spring, means for lifting the shuttle into a pick position through an arcuate path, a pivoted jaw opener with means for driving it at a greater angular speed than said shuttle during the initial portion of the stroke of said shuttle in its arcuate path, whereby said jaw opener is driven between the tines of said spring for opening said jaws and retaining them open during the greater portion of the stroke of said shuttle through its arcuate path, and cleaner bristles mounted within said path, adapted to wipe the surfaces of said jaws as the

shuttle and jaws are swept through said arcuate path, whereby foreign material, lint, broken threads, grease, and the like are removed from said gripper shuttle prior to its reaching the pick position.

4. In a weaving machine of the gripper shuttle type employing a shuttle having openable thread receiving jaws, a shuttle carrier for removably supporting such a shuttle, mechanism moving said carrier to a pick position, and cleaner bristles mounted within the path of said carrier for cleaning the shuttle preparatory to being brought into the pick position.

5. In a weaving machine of the gripper-shuttle type employing a shuttle having openable thread receiving jaws, a shuttle carrier for removably supporting such a shuttle, mechanism moving said carrier and shuttle to a pick position, and cleaning means mounted within the path of said carrier and shuttle for cleaning the shuttle jaws preparatory to being brought into the pick position.

6. In a weaving machine of the gripper-shuttle type employing a shuttle having openable thread-receiving jaws, mechanism for moving such a 25 shuttle to a pick position, mechanism for opening the jaws of the shuttle while the shuttle is being so moved, and means for cleaning the shuttle jaws while they are open.

7. In a weaving machine of the gripper-shuttle type employing a shuttle having openable thread-receiving jaws, a shuttle carrier for removably supporting such a shuttle, mechanism for moving said carrier and shuttle to a pick position, mechanism for opening the jaws of the shuttle while supported by the said carrier and while being moved to the pick position, and cleaning means mounted along the path of said carrier.
